DESIGN FOR A FASTENER PRONG RING

Thomas F. Slater, Waterbury, Conn., assignor to
Scovill Manufacturing Company, Waterbury,
Conn., a corporation of Connecticut

Application January 27, 1940, Serial No. 89,773

Term of patent 7 years

To all whom it may concern:

Be it known that I, Thomas F. Slater, a citizen of the United States, residing at Waterbury, county of New Haven, State of Connecticut, have invented a new, original, and ornamental Design for Fastener Prong Rings, of which the following is a specification, reference being had to the accompanying drawing, forming part thereof.

Fig. 1 is a top view of a fastener prong ring embodying my new design, and
Fig. 2 is a front elevation thereof.

I claim:

The ornamental design for a fastener prong ring, substantially as shown.

THOMAS F. SLATER.
